TURBINE

William Schwier, Milwaukee, Wis.

Application October 16, 1942, Serial No. 462,311

9 Claims. (Cl. 60—41)

This invention aims to provide novel means whereby rotation may be imparted to the rotor of a turbine, by impulses derived from successive explosions of a gaseous mixture. Another object of the invention is to improve the construction of the turbine. A further object of the invention is to supply novel means for cooling or affecting otherwise, the turbine and associated parts. A further object of the invention is to provide novel means for preparing the charge and delivering it into the turbine.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in side elevation, a device constructed in accordance with the invention;

Fig. 2 is an end elevation;

Fig. 3 is a vertical longitudinal section, showing the forward portion of the structure;

Fig. 3A is a longitudinal vertical section, supplementing Fig. 3, and disclosing the rear portion of the structure;

Fig. 4 is an elevation disclosing the gate;

Figs. 5, 6 and 7 are sections, taken, respectively, on the lines 5—5, 6—6 and 7—7 of Fig. 3;

Fig. 8 is a longitudinal section of the rotor, the abutment cylinder appearing in elevation, and the sleeves and correlated parts being shown spaced from the rotor and the abutment cylinder;

Fig. 9 is a sectional elevation showing one of the many mechanisms which may be employed for taking power from the rotor.

For convenience in describing the location of parts relatively to each other, and in order that the claims may be properly construed, that end of the machine which is marked by the letter A is to be considered as the forward end, the rear end being marked by the letter B such terms as "to the rear of," and the like, being employed accordingly.

Referring to Figs. 1, 2, 3 and 3A, there is shown a rear pedestal 1 and a forward pedestal 2. The forward pedestal 2 is a composite structure, including a foot 3, to which is secured the lower

part 4 of the base 5 of a vertical cylinder 6, the upper part 7 of the base 5 being formed integrally with the cylinder, and the base parts 4 and 7 being held together by securing elements 8, as shown best in Fig. 2.

A tubular carrier shaft 11 is provided, and is fixedly mounted in the rear pedestal 1, and in the cylinder base 5. The upper portion of the cylinder base 5 is supplied with a valve seat 10, of downwardly flared construction, communicating with the bore of the shaft 11, by way of a downwardly flared opening 9 in the carrier shaft.

Until further notice, the valve seat 10 and the opening 9 are to be viewed merely as a means for admitting fluid under pressure into the bore of the fixed shaft 11. That fluid, preferably, is gas produced by internal combustion, as in an engine of that type.

On the forward end of the base 5, a cap 12 is detachably secured, the cap having a central opening 14. An air inlet tube 15 is provided, and is disposed in the bore of the carrier shaft 11. The forward end of the air inlet tube 15 is

25 mounted in the cap 12, the rear end of the tube being mounted in a deflector block 16, having a downwardly and forwardly inclined surface 17. A bolt 18 or other securing element holds the deflector 16 and the rear end of the tube 15 in

30 the tubular shaft 11. To the rear of the tube 15, the fixed shaft 11 is supplied with a lateral outlet port 19. A partition 20 is held by a securing element 21 in the tubular shaft 11, and is located to the rear of the port 19. From the foregoing, it will be noted that the air tube 15 and the carrier shaft 11 are fixed against rotation.

A stator 22 is disposed about the carrier shaft 11. A nipple 23 has its inner end mounted in 40 the shaft 11, the outer end of the nipple being mounted in the stator 22. The rear wall 24 of the nipple has an outward and backward slant. On its outer surface, the stator 22 has abutment grooves 25, preferably of semicircular cross section, these grooves being shown in Figs. 5, 6 and 8. The abutment grooves 25 are disposed, each, in a slow spiral, having a pitch of about fifteen degrees.

The forward end wall 26 of the stator 22 has 50 ports 27, disposed close to the inner surface of the stator and the wall is provided, close to the shaft 11, with notches or seats 28.

An inner sleeve 29 is disposed about the shaft 11 and is connected thereto by securing elements 55 30 (Fig. 3). The sleeve 29 has an outstanding

flange 31, forming a shoulder. The inner member 32 of an anti-friction bearing surrounds the sleeve 29 and is held against the flange or shoulder 31 by a ring 33, threaded on the inner member of the anti-friction bearing. At its inner end, the sleeve 29 is supplied with longitudinally projecting fingers 34, which enter the seats 28 in the end wall 26 of the stator 22. It will now be seen that, by means of the fingers 34, the stator 22 is coupled to the sleeve 29, and through the instrumentality of the securing elements 30, the sleeve is connected to the tubular shaft 11, all of the parts specified being fixed.

About the stator 22 is disposed a tubular rotor 35, supplied on its inner surface with slow spiral grooves 36, preferably having a pitch of about twenty degrees. The grooves 36 preferably are V-shaped in cross section, as shown in Fig. 6, to prevent a substantially radial wall 37, adapted to receive fluid impact.

The rotor 35 and the end wall 26 of the stator 22 are equipped with cooperating seats 38, receiving a packing ring 39, supplied with circumferentially spaced recesses 40 (see Fig. 7) which, thinning the ring, tend to cause it to seat firmly, under pressure delivered, as hereinafter described, from the space between the stator 22 and the rotor 35. An outer sleeve 41 enters the forward end of the rotor 35 and has an outwardly projecting flange 42, secured to the end of the rotor by attaching elements 43.

The outer sleeve 41 is supplied with a recess defining a shoulder 44, and in the recess is mounted the outer member 45 of the aforesaid anti-friction bearing, the outer bearing member being held in place by a ring 46, threaded into the sleeve.

The structure at the rear end of the machine (Figs. 3A and 8) is the same as that at the forward end of the rotor 35, saving as hereinafter modified, and parts hereinbefore mentioned, and appearing therein are designated by numerals already used, the numerals being primed.

The differences between the structure at the forward end of the machine and the structure at the rear end of the machine are as follows:

The port 19' is an outlet port. The forward wall 24' of the nipple 23' is the inclined wall and has an outward and forward slant. The tube 15' is an air outlet tube.

Another difference resides in the structure to be found at the rear end of the fixed tubular carrier shaft 11. A plate 47 is secured against the rear end of the shaft 11 and has a cruciform opening 48. A cup-shaped gate 49 is mounted to rotate for adjustment on the rear end of the shaft 11 and has a cruciform opening 50, adapted to be brought more or less into registration with the opening 48 of the part 47, the gate being held in adjusted positions by means of set screws 51.

Assuming that rotation is imparted to the rotor 35, power may be taken from it in any desired way. For instance, a belt (not shown) may be engaged about the rotor 35. In Fig. 9, the rotor is designated by the numeral 52 and may have a track groove 53, receiving the periphery of a friction wheel 54, secured to a driven shaft 55.

Assuming that a means is provided for delivering fluid, such as gas, under pressure, through the opening 9 of the carrier shaft 11, the fluid moves inwardly in the bore of the shaft until the inclined surface 17 of the deflector 16 is encountered, whereupon the fluid travels outwardly through the nipple 23 and is discharged into the space between the stator 22 and the rotor 35. The fluid, cooperating with the grooves 36 of the

rotor 35 and the abutment grooves 25 of the stator 22, imparts rotation to the rotor. The fluid, proceeding rearwardly between the rotor 35 and the stator 22, moves inwardly through the nipple 23', the fluid being delivered into the bore of the fixed shaft 11, and finding an exit at the rear end of the shaft, under the governance of the gate 49. The opening 50 of the gate may be brought more or less into registration with the opening 48 in the part 47 and, thus, the back pressure may be regulated, the speed of rotation of the rotor 35 being changed accordingly.

Air enters the tube 15 of Fig. 3, through the opening 14 and, being impeded by the partition 20, can flow through the part 19, and forwardly around the nipple 24, through the ports 27 in the end wall 26 of the stator 22, and thence to the ring 39 and to and out of the anti-friction bearing 32-45. The air moves rearwardly, between the shaft 11 and the stator 22, and cooperates with the ring 39 and the bearing 32-45, in the way hereinbefore set forth, the over-plus of air being returned to the bore of the shaft 11, through the port 19' of Fig. 3A, the air leaving by way of the outlet tube 15'.

It appears from the foregoing that the turbine, including the bearing structure 32-45, will be adequately cooled: or if conditions are such that it is desirable to raise and maintain the temperature of the turbine, hot air, instead of cold, may be passed through the opening 14 of Fig. 3, into the inlet tube 15.

It is understood that adequate lubrication may be provided for any of the parts hereinbefore or hereinafter mentioned, the lubricating means forming no part of the present invention, since known systems of lubrication may be employed.

As shown in Fig. 3, the cylinder 6 is provided with oppositely disposed guide bores 56, in which reciprocate the depending, reduced fingers 57 of an inverted, U-shaped yoke 58 carrying a tappet 59 in its intermediate portion. The numeral 60 designates an inverted L-shaped plunger (Fig. 2) including a horizontal arm which passes through the tappet 59, the tappet and the yoke 58 being held in place by a nut 61 which binds the tappet against a shoulder 62 on the horizontal arm of the plunger. The vertical arm of the plunger 60 reciprocates in a guide 63 on the cylinder 6 and enters a casing 64, containing mechanism 65a for imparting reciprocation to the plunger and associated parts. The mechanism referred to may be of any desired sort, including a driven shaft 65.

In the cylinder 6, a piston 66 is mounted for reciprocation, the piston carrying piston rings 67. At its upper end, the piston 66 is supplied with a laterally outstanding flange 68, through which the fingers 57 of the yoke 58 pass. The fingers 57 of the yoke carry shoulders 69 adapted to engage the flange 68, and held in place by securing devices, such as cross pins 70. Compression springs 71 surround the yoke fingers 57 and bear at their upper ends against the flange 68 of the piston 66, the lower ends of the springs bearing against the upper end of the cylinder 6. The piston 66 is supplied at its upper end with a recess 72.

A valve 73 cooperates with the seat 10 and is carried by a stem 74, the stem being secured to the valve by means of a pin 75 and a nut 76, the nut being retained upon the stem through the instrumentality of a pin 77 or the like.

In the bottom of the recess 72 of the piston 66 is disposed a packing 78, through which the valve

stem 14 passes, the stem extending through a follower 19, disposed above the packing and threaded into the piston. A compression spring 80 bears on the follower 19 and is engaged at its upper end by a nut 81, threaded on the stem and held in place by a securing member 82 of any desired sort.

In Fig. 1, the means for admitting the gaseous fluid to the cylinder 6 is a pipe 83. In order to fire the charge, the cylinder 6 is supplied with any desired number of spark plugs 84 (Fig. 3).

Actuated by the mechanism 65a in the casing 64, the plunger 60 moves downwardly, carrying with it the yoke 58, the shoulders 69 causing the piston 66 to move downwardly, the springs 71 being compressed. The spring 80 holds the valve 73 in closed position, as the piston 66 moves downwardly, to compress the charge, and the effort of the spring may be varied by changing the position of the nut 81.

When compression has proceeded to a maximum, the compressed charge is fired by the spark plugs 84, the valve 73 being opened, when the tappet 59 on the yoke 58 comes into contact with the upper end of the valve stem 14. The compressed and exploded mixture passes through the opening 9 of Fig. 3, into the part 7, and does its work in turning the rotor 35, as has been explained hereinbefore. Any suitable means common in the art may be provided for preventing the piston 66 from forcing the fuel charge out by way of the pipe 83. For example, a check valve 83a may be disposed in the pipe.

The upstroke of the valve 73, to closed position, is brought about by the plunger 60 and associated parts, the springs 71 serving to aid in the upward movement of the piston 66.

Having thus described the invention, what is claimed is:

1. A turbine comprising a tubular carrier shaft and a stator disposed about the shaft, the stator having an end wall provided with a seat; a rotor disposed about the stator, a sleeve secured to the shaft and having a finger entering the seat, a bearing including inner and outer members, means for securing the inner bearing member to the sleeve, means for securing the outer bearing member to the rotor, and means for admitting fluid under pressure into the space between the stator and the rotor, by way of the bore of the shaft.

2. In a turbine, a tubular shaft, a stator disposed about the shaft and having an end wall provided with an outlet port, and means for securing the stator to the shaft; a rotor disposed about the stator, a bearing disposed between the rotor and the shaft, means for discharging fluid under pressure into the bore of the shaft, means for conducting the fluid from the bore to the space between the stator and the rotor, a deflector in the shaft, to the rear of the conducting means, the shaft having a side port located to the rear of the deflector and establishing communication between the bore of the shaft and the space between the shaft and the stator, a partition in the shaft, to the rear of the side port, and an air inlet tube disposed within the shaft and opening into the shaft between the deflector and the partition; the tube, the portion of the shaft which is between the deflector and the partition, and the outlet port, forming an air conduit leading to the bearing and constituting means for cooling the bearing.

3. A turbine constructed as set forth in claim 2 and wherein the conducting means is a nip-

ple mounted in the shaft and in the cylinder, and so located with respect to the side port that air will pass across the nipple, externally thereof, to cool the nipple as the air moves toward the bearing.

4. In a turbine, a tubular carrier shaft, a stator disposed about the shaft and having an end wall provided with an outlet port, and means for securing the stator to the shaft; a rotor disposed about the stator, a packing located between the stator and the rotor, means for discharging fluid pressure into the bore of the shaft, means for conducting the fluid from the bore to the space between the stator and the rotor, a deflector in the shaft, to the rear of the conducting means, the shaft having a side port located to the rear of the deflector and establishing communication between the bore of the shaft and the space between the shaft and the stator, a partition in the shaft, to the rear of the side port, and an air inlet tube disposed within the shaft and opening into the shaft, between the deflector and the partition; the tube, the portion of the shaft which is between the deflector and the partition, and the outlet port, forming part of an air conduit leading to the packing, and constituting means for cooling the packing.

5. A turbine constructed as set forth in claim 2, in combination with a packing disposed between the stator and the rotor, the end wall of the stator being spaced from the bearing, to permit air to have access to the packing and to cool the packing.

6. A turbine comprising a tubular carrier shaft, a stator disposed about the shaft and means for securing the stator to the shaft; a rotor disposed about the stator, an intermediate partition in the shaft, deflectors in the shaft, on opposite sides of the partition, air tubes in the opposite end portions of the shaft and opening through the respective deflectors, the shaft having side ports located between the partition and the respective deflectors, conducting means establishing communication between the bore of the shaft and the space between the stator and the rotor, the conducting means being located outwardly of the respective deflectors, and means for discharging pressure fluid into one end portion of the shaft, about the corresponding inlet tube, and through the corresponding conducting means, the tubes and the ports forming a cooling conduit, of which the space between the shaft and the stator forms a part.

7. A turbine constructed as set forth in claim 5 and wherein the inner surface of the rotor and the outer surface of the stator have cooperating, slow-spiral grooves, the pitch of the grooves of the rotor differing from the pitch of the grooves of the stator cylinder.

8. A turbine constructed as set forth in claim 6, and wherein the inner surface of the rotor and the outer surface of the stator have cooperating, slow-spiral grooves, the grooves of the rotor having a greater pitch than the grooves of the stator.

9. A turbine comprising a tubular carrier shaft and a stator disposed about the shaft, a rotor disposed about the stator, a connection between the shaft and the stator and affording communication between the bore of the shaft and the space between the stator and the rotor, and means for discharging fluid under pressure into the bore of the shaft, the fluid-discharging means comprising a compression cylinder mounted on the shaft and having a valve seat, a valve

cooperating with the seat, a stem for the valve, a piston slideable on the stem and in the cylinder, the space between the valve and the piston constituting a compression chamber, means for holding the valve closed whilst the piston makes a compression stroke, a member movably mounted on the compression cylinder, said member be-

ing engageable with the stem, to open the valve at the end of the compression stroke of the piston, means for firing a charge in the compression chamber, a fuel intake for the compression cylinder, and means for actuating said member.

WILLIAM SCHWIER.
